UNITED STATES PATENT OFFICE.

FRANK W. KNIEBUSCH, OF WOODSTOCK, ILLINOIS.

GAME APPARATUS.

Application filed May 11, 1925. Serial No. 29,579.

To all whom it may concern:

Be it known that I, FRANK W. KNIEBUSCH, a citizen of the United States, residing at Woodstock, in the county of McHenry and 5 State of Illinois, have invented certain new and useful Improvements in a Game Apparatus; and I do declare the following to be a full, clear, and exact description of the invention, such as will enable others skilled in 10 the art to which it appertains to make and use the same.

My invention aims to provide a novel type of game analogous to an ordinary bowling alley, but provided with a novel arrangement of stalls or pockets adapted to receive a ball rolled down the alley, and provided with means for indicating the pocket into which the ball has entered, even though the pockets may be obscured from view, below 20 the alley.

With the foregoing and minor objects in view, the invention resides in the novel subject matter hereinafter described and claimed, the description being supplemented 25 by the accompanying drawing.

Figure 1 is a longitudinal sectional view through a game apparatus constructed in accordance with my invention.

Figure 2 is a top plan view.

Figure 3 is a horizontal sectional view on line 3—3 of Fig. 1.

Figures 4 and 5 are vertical transverse sectional views as indicated by lines 4—4 and 5—5 of Fig. 1.

Figure 6 is an enlarged vertical longitudinal section of a fragment of the apparatus, as indicated by line 6—6 of Fig. 4.

Figure 7 is a side elevation of the movably mounted barrier hereinafter described, 40 showing the partition plates carried thereby and forming therewith the above mentioned pockets or stalls.

In the drawing above briefly described, the 45 numeral 1 designates a horizontally elongated casing which may be of any desired proportions, but is preferably of approximately thirty feet in length. The top 2 of this casing forms a bowling alley and its bottom 3 constitutes means for returning the 50 bowling balls to a suitable ball rack 4 at the front end of the casing, one of the balls being indicated at 5 in Fig. 1.

At the rear end of the casing 1, a cabinet 55 6 is provided containing electric lights 7 and provided with transparent front panels 8 bearing legends to be used in keeping the

score of the game. These legends preferably represent a "Strike", a "Spare", "Nine pins", "Eight pins", and "Seven Pins". Provision is made, hereinafter described, for 60 completing the circuits of the electric lights 7, and it will be understood that one of these lights is disposed behind each panel 8. Thus, the success of the balls rolled down the alley, is indicated to the players. The only balls 65 which effect illumination of the lights 7, are those passing through an opening 9 in the rear portion of the alley 2, and a gap 10 is provided at the rear end of this alley to permit any balls which do not pass through 70 said opening 9, to drop into the interior of the casing 1, so that they can return to the rack 4. Within the gap 10, a loosely hung 75 strike cushion 11 is preferably provided, and a bumper 12 may be employed behind this cushion, so that noise is reduced to the minimum when playing the game.

Within the casing 1, is an inclined ball chute 13 which is arranged to receive all balls passing through the opening 9. This 80 chute declines from the rear edge of this opening to the bottom 3 of the casing 1, and transversely, it extends from one vertical side wall 14 of the casing, into spaced relation with the opposite side wall 15 of said 85 casing, the last named portion of the chute being provided with an upstanding wall 16 which prevents the balls from running laterally therefrom. Leading to this wall 16 and extending diagonally from the wall 14, is 90 a ball-guiding strip 17 which is secured to the bottom 3 and serves to guide the balls from the gap 10, into the space between the walls 15 and 16.

At the lower end of the chute 13, I mount 95 a transverse barrier 18, spring hinges 19 being preferably employed for this purpose, so as to normally hold the barrier in an upright position. Vertical partition plates 20 are carried by and project rearwardly from the barrier 18 to co-operate therewith in forming a plurality of stalls or pockets to receive the balls passing through the opening 9, and the chute 13 is by preference provided with a plurality of upstanding, padded 100 pegs 21, between which the balls must pass before they can enter any of the pockets. These pockets are equal in number to the electric lights 7, and normally open switches 22 are provided for said lights, in said pockets. 105 These switches are preferably carried by the barrier 18 and whenever a ball comes 110

in contact with one of said switches, the latter is closed by said ball, with the result that the light 7 in circuit with the closed switch, is illuminated. Thus, even though 5 the pockets or stalls are below the alley 2, a light 7 will disclose into which of the stalls or pockets, a ball has entered, after passing through the opening 9.

For clearing the stalls or pockets of balls, 10 I provide any preferred means for swinging the barrier 18 forwardly, as shown in dotted lines in Fig 6, permitting the balls or ball to roll onto the bottom 3, for return to the rack 4, said bottom being preferably 15 provided with a guiding rail 23, causing the balls to roll along the side wall 15.

In the present showing, for swinging the barrier 18 forwardly, I have provided a longitudinal rod 24 within the casing and 20 connected at its rear end to said barrier by a link 25, while the front end of said rod is formed with a hand-grip or the like 26, disposed at the front end of the casing 1.

The game is played very much like ordinary bowling, and any ball which is rolled along the alley 2, but passes through the gap 10, does not add to the player's score. However, any ball passing through the opening 9, necessarily finds its way to one 25 of the pockets or stalls at the lower end of the chute 13, and these pockets or stalls have different counting values, which are shown by the legends on the panels 8. If a ball passing through the opening 9, enters 30 the "strike" pocket or stall, the light 7 for the "Strike" legend is illuminated, and the other lights are of course lighted whenever the ball reaches their respective pockets.

The apparatus is rather simple and inexpensive, may be readily used in numerous places in which it is inadvisable to install an ordinary bowling alley, and will give a great deal of amusement. As excellent results are obtainable from the general construction disclosed, such construction may well be followed. However, within the scope of the invention as claimed, numerous modifications may be made.

I claim:

50 1. A game comprising an alley, a chute under said alley to receive a ball from the same, ball-receiving pockets at the lower end of said chute having different counting values, and ball-actuated indicating means 55 for disclosing into which pocket the ball enters.

2. A game comprising an alley, a chute under said alley to receive a ball from the same, a movably mounted barrier at the

lower end of said chute, ball-receiving stalls 60 formed in part by said barrier and having different counting values, ball-actuated indicating means for disclosing into which stall the ball enters, means for moving said barrier to clear the stalls of balls, and ball-returning means from the stalls to the front end of the alley.

3. A structure as specified in claim 2; said stalls comprising said barrier, and partition plates projecting from said barrier 70 toward the upper end of the chute.

4. A game comprising a horizontally elongated casing whose top forms an alley, a chute in the casing adapted to receive a ball from the alley, ball-receiving pockets at the 75 lower end of the chute having different counting values, and ball-actuated indicating means for disclosing into which pocket the ball enters.

5. A game comprising a horizontally elongated casing whose top forms an alley and whose bottom constitutes a ball-return runway, a communicating opening being provided from the rear end of the alley to the interior of the casing, a forwardly declined chute in the rear portion of the casing spaced inwardly from one side wall of the latter, the alley being formed with a ball opening at the upper end of said chute, ball-receiving pockets at the lower end of the chute and having different counting values, ball-actuated indicating means for disclosing into which pocket a ball from said opening enters, and means for clearing the pockets of balls, permitting the latter to 95 roll upon said ball-return runway.

6. A game comprising a horizontally elongated casing whose top forms an alley and whose bottom constitutes a ball-return runway, a communicating opening being provided from the rear end of the alley to the interior of the casing, a forwardly declined chute in the rear portion of the casing spaced inwardly from one side wall of the latter, the alley being formed with a ball opening at the upper end of said chute, a movably mounted barrier at the lower end of said chute, ball-receiving stalls formed in part by said barrier and having different counting values, ball-actuated indicating means for disclosing into which stall a ball from said opening enters, and means for moving the aforesaid barrier to clear the stalls of balls, permitting the latter to roll 100 upon said ball-return runway.

In testimony whereof I have hereunto affixed my signature.

FRANK W. KNIEBUSCH.
